UNITED STATES PATENT OFFICE.

NICHOLAS SCHUSTER, OF WESTMINSTER, LONDON, ENGLAND.

COKE-OVEN.

1,186,687.

Specification of Letters Patent. Patented June 13, 1916.

Application filed December 21, 1914. Serial No. 878,420.

To all whom it may concern:

Be it known that I, NICHOLAS SCHUSTER, subject of the Emperor of Germany, residing at 7 Princes street, in the city of Westminster, London, England, have invented certain new and useful Improvements in Coke-Ovens, and of which the following is a specification.

This invention relates to coke ovens of 10 that type in which the gas for combustion is admitted through passages in the structure below the heating flues, and in which flues, running parallel with the said gas passages and also below the heating flues, 15 serve for the exit of the products of combustion.

The primary object of the present invention is to provide means whereby the gas for combustion admitted to a coke oven shall 20 not become too highly heated during its flow in the passages beneath the ovens. It is known that if the gas introduced for combustion reaches too high a temperature, decomposition and deposits of free carbon are 25 brought about by the radiant heat prior to the gas passing into the combustion chambers.

Where passages through which the gas for combustion is introduced into the combustion flues of a coke oven, extend any considerable depth into the structure, and where such gas passages are at intervals throughout their length formed with delivery nozzles or apertures at intervals apart 35 through which the gas passes into the combustion flues, the pressure of the gas so delivered into the heating flues through nozzles is greater adjacent to the entrance of the gas passages, and diminishes toward 40 those ends farthest away from the supply, and a further object of the present invention is to provide an improved construction by which this disadvantage can be entirely or in great part overcome, and at the same 45 time to so locate the exit nozzles from the gas passages relatively to the surrounding structure, that the said gas exit nozzles cannot be choked by falling dust or other debris.

According to this invention, in order to 50 prevent the gas, passing through the gas admittance passages in the structure, becoming too highly heated, I provide, adjacent and parallel to such passages, a cooling passage extending entirely through the structure and arranged between each gas passage and exit flue for the products of com-

bustion, the cooling passages being open to the atmosphere, and in some cases I connect such air cooling passages at some point in between their ends with one or more of the 60 flues in the oven which is in communication with the uptake, so that a current of cool air is automatically drawn through said air cooling passages.

In order to regulate the flow of gas for 65 combustion to the combustion flues, I make the passage extending into the structure, into which the gas for combustion is admitted, tapering at that end farthest away from the supply, that is to say the inner end of 70 the passage is formed of gradually decreasing cross sectional area, and in conjunction with such an arrangement I in some cases provide an auxiliary parallel passage supplied at its outer end with combustible gas 75 and communicating at its inner end with and near to the inner end of the first mentioned gas passage so as to provide an auxiliary supply of gas to the main or principal gas passage. Beyond this I locate the nozzles of the gas passages within a chamber having inwardly and upwardly inclined side walls, one of the walls overhanging the nozzles, and I provide within the chamber, a recess parallel to the nozzles to receive any 80 debris, all as hereafter described.

I will describe my invention with reference to the accompanying drawings which show an example of construction and arrangement as applied to a regenerative coke 90 oven of the kind referred to in my Patent application No. 878,419, of even date here-with.

Figure 1 is a longitudinal section of the right hand half of the structure, this section being taken through the heating flues in one of the side walls between two ovens, and Fig. 1^A shows the left hand half of the same coke oven, this section being taken through the adjacent coking chamber. Fig. 2 is a 100 transverse vertical section of the structure taken about the line X—Y of Fig. 1^A and drawn to a slightly larger scale than the latter figure. Fig. 3 is a horizontal section taken about the line X¹—Y¹ of Fig. 2. 105

Referring to the drawings, particularly Figs. 1, 1^A and 2, the gas inlet passages 1 extend from the exterior face of the structure beneath the combustion flues 2 in each side wall 3 dividing the coking chambers 4, and in the construction shown the said gas passages 1 terminate just before reaching the 110

center of the combustion flues in the side walls as shown at Fig. 1, and other similar gas passages extend from the opposite exterior face of the structure. Gas is supplied 5 to the passages 1 from the main 5 through a pipe 6 and nozzles 7 controlled by cocks 8. Each gas passage 1 in the structure is provided or formed with delivery nozzles or apertures 9, through which the gas passes 10 into the combustion flues 2, and by regulating the cocks 8 gas can be admitted to the right hand half of the combustion flues, Fig. 1, and shut off from the other half, Fig. 1^a, or vice versa.

15 According to the present invention cooling passages 24 are formed in the structure one on each side of the gas passages 1 and extending parallel therewith, the said cooling passages 24, as shown in Fig. 3, being open 20 at their ends to the atmosphere and extending entirely through the structure between the said gas passages 1 and passages 16, through which passages 16 the products of combustion pass. The cooling passages 24 25 may also be connected by passages 25 with the passages 16, and therefore indirectly with the uptake, and consequently a current of cool air flows through the cooling passages 24 from the open ends thereof, and 30 maintains the gas passing through the gas passages 1 at a temperature below the point at which decomposition of the heating gas sets in, say about 420° C.

In the particular coke oven to which the 35 invention is shown applied in the drawings merely by way of example, each of the passages 16 is connected by a passage such as 17, Figs. 1^a and 3, with one of a plurality of regenerating chambers formed in two pairs 40 of tunnels 19, Figs. 1, 1^a and 2, constructed in the base of the structure, the said passages 16 beneath the sole of the coking chamber being connected by passages 18, Figs. 1^a and 2, with the bases of the combustion flues 45 2, so that of the two passages 16 under one of the coking chambers for instance, one of the said passages serves for the admittance of heated air from a regenerating chamber, while the other passage 16 at the same period 50 serves for the exit of the products of combustion, which latter pass through another regenerating chamber; at another period the functions of the passages 16 are reversed.

Each of the gas passages 1 formed in the 55 structure upon opposite sides, is constructed of uniform cross sectional area for the greater part of its length, and its end farthest away from the supply is formed tapering as at 26 Fig. 1, whereby I am enabled 60 to equalize the pressure and flow of the gas through the nozzles 9. I further in some cases provide an auxiliary gas passage 27 fed through the supply pipe 6, the said passage 27 opening into the gas passage 1 where 65 the tapered portion thereof commences, and

so providing an auxiliary supply of gas to the gas passage 1.

In order to prevent debris (which it is possible may descend the combustion flues 2) choking the gas nozzles 9, I locate the said 70 gas nozzles 9 slightly on one side of the base of a gas chamber 28, the said chamber 28 being constructed with inclined side walls which approach each other before they reach the opening of said gas chamber 28 into the combustion flues 2 as shown at Fig. 2, and in such a manner that one of the side walls overhangs the nozzles; and at the opposite 75 side of the chamber 28 I form a recess in the base thereof to receive debris, so that debris 80 passing into the chamber 28 will fall into the recess 29 and not tend to choke the nozzles 9. Just before the chamber 28 opens into the combustion flues 2, the said chamber may be increased in width slightly, as indicated at 85 Fig. 2.

What I claim as my invention and desire to secure by Letters Patent is:—

1. In a coke oven of the type specified; a structure having in combination a series 90 of separate coking chambers formed therein parallel to each other, the side walls of said coking chambers each having a heating flue formed therein, said structure having combustible gas supply passages communicating with each heating flue and extending in the structure below said heating flues, means for supplying said gas to said gas supply passages and for controlling said gas supply, flues for the exit of products of 100 combustion extending beneath said coking chambers running parallel with said gas passages and communicating with said heating flues, said structure being formed with air cooling passages each passing entirely 105 through said structure being open at both ends to the atmosphere and located one on each side of said gas passages and between said gas passages and said flues through which products of combustion pass, in order 110 to maintain the gas passing through said gas passages at a temperature below the point at which decomposition of said gas sets in.

2. In a coke oven of the type specified; a 115 structure having in combination a series of separate coking chambers formed therein parallel to each other, the side walls of said coking chambers each having a heating flue formed therein, said structure having combustible gas supply passages communicating with each heating flue and extending in the structure below said heating flue, means for supplying said gas to said gas supply passages and for controlling said gas supply, 120 flues for the exit of products of combustion extending beneath said coking chambers running parallel with said gas passages and communicating with said heating flues, said structure being formed with air cooling pas- 125

ing flues, said structure being formed with air cooling passages each passing entirely through said structure being open at both ends to the atmosphere and located one on each side of said gas passages and between said gas passages and said flues through which products of combustion pass, in order to maintain the gas passing through said gas passages at a temperature below the

point at which decomposition of said gas 15 sets in.

In witness whereof I have hereunto set my hand in the presence of two witnesses,

NICHOLAS SCHUSTER,

Witnesses:

THOMAS W. ROGERS,

WILLIAM A. MARSHALL.
